PROTECTIVE HEADGEAR

Joseph B. Dym, Pittsburgh, Pa., assignor to Mine
Safety Appliances Company, Pittsburgh, Pa.,
a corporation of Pennsylvania

Application November 7, 1936, Serial No. 109,730

9 Claims. (Cl. 2—181)

This invention relates to head-gear and more particularly to protective head-gear for industrial use.

In order to reduce manufacturing costs it has been the standard practice heretofore to manufacture certain types of head-gear, such as protective or safety head-gear, in only a few, and preferably one, standard size, which was provided with adjustable head-engaging means to thereby adapt the head-gear to fit heads of various shapes and sizes. However, the use of adjustable means, as for example, adjustable head-bands, has occasioned difficulty due to the fact that the adjusting means either did not provide a satisfactory fit after adjustment or resulted in an off-center mounting of the head-gear upon the head. Again, adjustable head-bands were apt to be relatively complicated and thereby expensive and were often difficult and time-consuming to adjust. Likewise, changes from the largest to the smallest head size often resulted in a wrinkled or unsatisfactory head-band support for the head-gear.

It is the general object of my invention to overcome the foregoing and other difficulties of known adjustable size head-gears by the provision of a relatively simple and inexpensive, but sturdy and comfortable head-gear of a standard size having a quickly replaceable head-band of any desired particular size.

Another object of my invention is to provide a head-gear having an adjustable head-engaging cradle and a removable head-band whereby the head-gear can be adapted to comfortably fit heads of widely varying shapes and sizes, in a minimum of time and with the head-gear being properly centered upon the head of the wearer.

The foregoing and other objects of my invention are achieved by the provision of a head-gear comprising a crown of standard size having an adjustable cradle therein and a removable head-band of a particular size. The head-band is removably held in the crown by suitable means, such as snap fasteners, which have one half of each fastener secured to the head-band by tapes extending substantially parallel thereto but with the portions of the tapes adjacent the fasteners being unsecured to the head-band. The other halves of each fastener are secured to the crown and function to fasten the cradle thereto.

For a better understanding of the invention, reference should be had to the accompanying drawing wherein Fig. 1 is a bottom plan view of one embodiment of a head-gear incorporating

the features of my invention; Fig. 2 is a vertical sectional view of the head-gear of Fig. 1 taken on line II—II thereof; Fig. 3 is an enlarged fragmentary sectional view taken on line III—III of Fig. 2; Fig. 4 is a modification of the securing means of Fig. 3; and Fig. 5 is another modification of the securing means of Fig. 3.

While the principles of my invention are broadly applicable to the manufacture of any type of head-gear, such as hats, caps, sun, military, or police helmets, and the like, they are particularly applicable to the manufacture of safety or protective head-gear for industrial use, as in mines, and accordingly the invention has been so illustrated and will be so described.

Having particular reference to Figs. 1 and 2 of the drawing, the numeral 10 indicates generally a rigid crown of a protective head-gear which in the embodiment of the invention illustrated is formed with an integral brim 12. The 10 crown and brim are stamped or molded, usually in a single or standard size, from any suitable material, such as metal, synthetic resin, hard rubber, or asphaltic composition with or without fabric reinforcement. In all events, the 15 resulting crown and brim are adapted to resist 20 blows or impacts and to protect the wearer of the hat. Secured to the crown 10 is an inverted cradle or hammock which is adapted to engage 25 with the wearer's head and support the hat. 30 In the form of the invention shown, the cradle comprises a plurality, generally four, of tapes 14, which are secured at their ends to the crown 10 adjacent the brim 12. Preferably this is accomplished by the socket halves 16 of snap 35 fasteners which extend through the crown 10 as shown in Fig. 2 and tightly secure the ends of the tapes 14 to the crown. If desired, the tape 40 ends may be reinforced by an additional tape portion 18 stitched thereto. The upper ends of 45 the tapes 14 are turned back upon themselves and stitched to form loops 20 which receive a draw string 22 whereby the size of the cradle can be adjusted to fit the head of the hat wearer.

Removably secured in the crown 10 is a hat 45 band 26 of a particular size. The band 26 can be of any usual or known construction but preferably comprises a leather strip 28 bent around a flat strip 30 of fiber and secured thereto as by stitching 32. The hat band is removably mounted in the crown 10 and for this purpose tapes 34 are secured near their ends (see Fig. 3) to the band 26 as by stitching 36 adjacent each of the socket fasteners 16. Near the center and unsecured portion of each tape 34 a pin half 38 of a 50 55

fastener member is secured which as shown in Fig. 2 is adapted to be received in a socket fastener portion 16. The tape 34, having a flattened V-shape, as best seen in Fig. 3, and secured 5 to the head-band 26 only at its ends, has an unsecured portion near the pin fastener member 38 so that, while the tape extends substantially parallel to the head-band 26, it is free to move toward and from the band with a limited movement whereby the tape and pin fastener 38 can 10 be secured to a socket fastener 16. It should be noted also that I preferably secure the pin fastener 38 to each tape 34 at a point vertically offset from the point where the stitching 36 fastens the ends of the flattened V-shaped tapes 15 to the head-band 26. This arrangement of parts not only allows movement of the downwardly extending flap-like portions of the tapes toward or from the head-band without wrinkling the 20 head-band but also secures the crown 10 to the head-band so that the weight of the crown is borne directly to the head-band substantially in the flat plane of the tapes.

In Fig. 4 I have illustrated a modified form of 25 tape for securing the head-band to the crown. More specifically, a short rectangular strip of tape 34a is provided which is secured near its top to a head-band 26a by stitching 36a. The tape 34a is provided with a pin half of a fastener 38a similar to fastener 38 whereby the tape and head-band can be quickly secured to the socket fastener 16 carried by the crown 10.

Another modification of the means for releasably securing the head-band to the crown is 35 shown in Fig. 5 wherein a tape 34b of relatively sharp V-shape is employed. The tape 34b is secured to a head-band 26b by stitching 36b, as illustrated, and pin halves of fasteners 38b fastened to the ends and bottom of V-tape 34b 40 complete the assembly.

The function and operation of the securing means of Figs. 4 and 5 are similar to that of the securing means shown in Fig. 3 except that the means of Fig. 5 require additional socket fasteners on the crown 10, as will be understood.

I have found that by the construction described I am able to mold or stamp a head-gear having a crown and associated portions of a single size and that head-bands of any particular size can be 50 quickly fastened in the crown so as to adapt the head-gear to use by a person having a head of a particular head-band size. In practice, the store or company selling or using my improved head-gear provides the head-gears in a single standard size and head-bands of a wide variety of sizes. The purchaser of the head-gear then buys or 55 obtains the crown of standard size and a head-band of his particular head size and quickly snaps it into the crown. The cradle is adjusted by means of the draw string 22 so as to properly engage with the head of the wearer of the head-gear.

From the foregoing it will be seen that the 60 objects of my invention have been achieved by the provision of an improved head-gear, particularly of the safety or protective type, having a standard crown size and a quickly removable head-band whereby any particular size head-band can be employed. The means for mounting 65 the head-band in the crown are inexpensive, rugged, and long-wearing. They are readily operated by the ordinary individual to secure the head-band in the head-gear in an unwrinkled and centered relation regardless of whether the particular head-band is the smallest or largest size.

The principles of the invention can be employed with caps, hats, sun helmets, and like head-gear of various kinds and characteristics and are particularly adapted for use with protective or safety head-gear.

While, in accordance with the patent statutes, one embodiment of my invention has been illustrated and described in detail, it should be appreciated that the invention is not limited thereto or thereby but is defined in the appended claims. 10

I claim:

1. A protective head-gear comprising a rigid blow resistant crown of a standard size, a brim formed integral with the crown, a head cradle in the crown and adapted to engage the head of the wearer of the head-gear, means comprising socket halves of snap fasteners securing the ends of the cradle to the crown, means for adjusting the size of the cradle, a head-band of a particular head size, means removably securing the head-band to 20 the crown, said last-named means including tapes secured adjacent their ends to the band, a pin half of a snap fastener secured to each tape adjacent its center and vertically below the points at which the tapes are secured to the band, said pin half of a snap fastener being removably received in a socket snap fastener. 25

2. A protective head-gear comprising a rigid blow resistant crown, a head cradle in the crown and adapted to engage the head of the wearer of the head-gear, means comprising socket halves of snap fasteners securing the cradle to the crown, means for adjusting the size of the cradle and the distance between the crown and the unsecured portion of the cradle, a head-band, means removably securing the head-band to the crown, said last-named means including flattened V-shaped tapes secured adjacent their ends to the band, a pin half of a snap fastener secured to each tape adjacent the bottom of the V and removably received in a socket snap fastener. 30

3. A protective head-gear comprising a rigid blow resistant crown, a head-band, means removably securing the head-band to the crown, said last-named means including flattened V-shaped tapes secured adjacent their ends to the band, means secured to each tape adjacent the bottom of the V and removably secured to the crown. 35

4. A protective head-gear comprising a rigid blow resistant crown, a head cradle in the crown and adapted to engage the head of the wearer of the head-gear, means comprising snap fasteners securing the cradle to the crown, means for adjusting the size of the cradle, a head-band, and means removably securing the head-band to the crown and engaging with the snap fasteners. 40

5. A head-gear comprising a standard size crown, a head cradle in the crown and adapted to engage the head of the wearer of the head-gear, means comprising halves of snap fasteners 50 securing the cradle to the crown, means for adjusting the size of the cradle, a head-band of a particular head size, and mating halves of snap fasteners securing the head-band to the crown and engaging with the first mentioned fastener 65 halves.

6. A head-gear comprising a crown of a standard size, a head-band of a particular size removably secured therein by snap fasteners, one half of each fastener being secured to the crown, the other half of each fastener being secured to the head-band by tapes extending substantially parallel to the head-band but secured thereto along a substantially horizontal line at the upper edge of the tape. 70

7. A protective head-gear comprising a rigid blow resistant crown, a brim formed integral with the crown, an inverted head cradle in the crown and adapted to engage the head of the wearer of 5 the head-gear, means comprising female halves of snap fasteners securing the cradle to the crown, means for adjusting the size of the cradle and the distance between the crown and the unsecured portion of the cradle, a head-band, means removably securing the head-band to the crown, said 10 last-named means including loops secured adjacent their ends to the band, a male half of a snap fastener secured to each loop adjacent its center and removably received in a female snap fastener.
15. 8. A head-gear comprising a crown of standard size, a head-band of a particular size, tapes secured to the band at circumferentially spaced points and each having a downwardly extending

flap portion free for movement to and from the band and the crown, quickly removable means for securing the flap portions of the tapes to the crown, and an adjustable cradle secured to the crown by the means securing the flap portions 5 of the tapes to the crown.

9. A head-gear comprising a crown of standard size, a head-band of a particular size, snap fasteners removably securing the head-band to the crown, V-shaped tapes securing the snap fasteners to the head-band, said tapes being secured by the upper legs of the V to the head-band and carrying the snap fasteners at the bottom of the V, the tapes extending substantially parallel to the head-band but with the portions of the tapes 15 carrying the fasteners being spaced from the head-band.
